UNITED STATES PATENT OFFICE.

EUGENE E. STUVER, OF BLUEMOUND, ILLINOIS.

CLASP FOR SUSPENDER-ENDS.

SPECIFICATION forming part of Letters Patent No. 736,170, dated August 11, 1903.

Application filed May 21, 1903. Serial No. 158,159. (No model.)

To all whom it may concern:

Be it known that I, EUGENE E. STUVER, a citizen of the United States, residing at Blue-mound, in the county of Macon and State of Illinois, have invented a new and useful Improvement in Clasps for Suspender-Ends, of which the following is a specification.

My invention relates to an improvement in suspenders, and is more particularly adapted in its application to suspender ends or tabs, the objects being to provide a device of this character which, primarily, will avoid the use of buttons or buttonholes on the trousers or other garment to be supported. My improvement contemplates the substitution therefor of a neat, simple, and easily-operated device which will positively engage the material of the garment and removably retain it until it is desired to release the garment from the suspender; and it consists in an inexpensive gripping device applied to the tabs of the suspenders and adapted to receive between its jaws the material of the garment, the jaws adapted to releasably grasp the material and yet not injure it in the slightest degree.

To these ends my invention consists in certain novel combinations of parts, such as will be more fully described hereinafter, and particularly set forth in the claim.

30 In the accompanying drawings, Figure 1 is an enlarged view, in side elevation, of my improvement attached to a suspender-tab and grasping a piece of material; and Fig. 2 is a perspective view with the jaws open.

35 The clasp is composed of two members or plates 1 and 2, hinged together at their upper ends, as at 3, in a suitable manner, the pin-tle 4 of the hinge constituting a ring, permitting the attachment of the clasp to the suspender end or tab 5. The opposite or free ends of the plates 1 and 2 are widened and provided with inwardly-extending jaws 6. These jaws do not abut, but overlap, one another in order to prevent any injury to the 45 garment. Supported on plate 2 and passing loosely through apertures 7 is a staple 8, curved or bent in the arc of a circle the center of which is the hinge, and hinged upon the cross-bar of this staple is a clamping-lever 50 9, provided with a cam 10, which is adapted

to engage plate 1 and force it toward plate 2, pressing the jaws together and clamping the garment material therebetween. The jaws are held together by reason of the resiliency of the plates, the form of the lever and cam, and by the position taken by the cam and lever in closing the jaws, in which the cam and the free end of the lever are on opposite sides of the pivotal support.

To release the garment, all that is necessary is to lift the lever, whereupon the pressure is removed and the material can be withdrawn from the jaws.

The plates are preferably constructed of some resilient material, and they may be spread apart and the jaws opened whenever the lever is swung backward or open, as shown in Fig. 2. The staple is formed or bent into the arc of a circle to permit plate 1 to move up and down thereon on its hinge without binding.

It is evident that many slight changes might be made in the form and arrangement of the several parts described without departing from the spirit and scope of my invention, and hence I do not wish to limit myself to the exact construction herein set forth; but

Having thus fully disclosed my invention, what I claim as new, and desire to secure by Letters Patent, is—

A suspender-clasp comprising two plates hinged together at one end and having jaws at the free ends, one jaw having holes therein, a staple extending through and fitted to these holes, said staple bent in the arc of a circle with the hinge as its center and the ends of the staple secured to the other plate, and a lever hinged to the staple center and provided with a rounded cam which forces and locks, the jaws together when swung inwardly against the adjacent jaw.

In testimony whereof I have signed this specification in the presence of two subscribing witnesses.

EUGENE E. STUVER.
